UNITED STATES PATENT OFFICE

109,866

DESIGN FOR A SHOE

Charles H. Caldwell, Brockton, Mass., assignor to
Geo. E. Keith Company, Campello, Mass., a
corporation of Massachusetts

Application December 28, 1937, Serial No. 73,899

Term of patent 3½ years

To all whom it may concern:

Be it known that I, Charles H. Caldwell, a citizen of the United States, residing at Brockton, in the county of Plymouth and State of Massachusetts, have invented a new, original, and ornamental Design for a Shoe, of which the following is a specification, reference being had to the accompanying drawing, forming part thereof.

In the drawing:

Figure 1 is a top plan of a shoe showing my new design; and

Figure 2 is a side elevation of the same.

Both sides of the shoe present substantially the same appearance.

As the design is applicable to shoes of various shapes and styles the representation of shoe is merely conventional, for showing an application of the design.

The essential feature of the invention resides in making the tip plain, the quarters plain, and

the tongue and flaps over the tongue plain, and the mid-portion of the vamp smooth but decorated with rows of small perforations arranged in wavy lines, bordered by stitching, these bordered rows being separated from each other by broader wavy linear spaces defined by the said wavy lines of stitching and containing larger perforations of segmental shape, successive individuals of these larger perforations being staggered and reversed at the successive troughs and crests of each wavy stitch line; with some of said linear wavy rows, wavy stitching and wavy spaces crossing over the whole width of shoe below the tongue and with some of them rising from the sole to the said plain mid-area overlying the tongue.

I claim:

The ornamental design for a shoe, as shown and described.

CHARLES H. CALDWELL.
